SEPARATING SYSTEM

Charles Wesley Boag, Milwaukee, Wis., assignor
to The Heil Co., Milwaukee, Wis., a corpora-
tion of Wisconsin

Application October 24, 1936, Serial No. 107,395

2 Claims. (Cl. 209—26)

The present invention relates in general to improvements in the art of treating commodities such as forage, and relates more specifically to an improved system for cooling, grading and for separating refuse from forage or the like which is being conveyed by air from a source of treatment such as a drier.

5

Generally defined, an object of my present invention is to provide an improved system for automatically and effectively conditioning the product delivered from a hay drier or the like, so that the commodity will be ready for final reduction and merchandizing.

Remarkable results have recently been attained in the production of food for poultry and the like, by passing forage such as alfalfa immediately after it has been cut, through a rotary drier wherein the material is simultaneously effectively dried and transported by a mixture of air and hot gases of combustion. The mixture of forage and gas is ordinarily drawn through the drying drum by means of a suction fan, and is delivered by the main fan through a cyclone or similar separator from whence the separated material has heretofore ordinarily been discharged directly either to bags and other containers, or to a disintegrating mill for final reduction. I have found that the dry material thus delivered from the primary separator is still quite hot and frequently contains refuse such as stones or pieces of metal, the presence of which in the final product is extremely objectionable. When the dried commodity is passed through a rotary impact pulverizer such as is ordinarily used for final disintegration, it is further heated by the impact and abrasive actions, and the presence of foreign objects such as stones and metal may produce sparks which will ignite the dry forage in the reducing mill. It is therefore very desirable to cool the product as much as possible after it leaves the initial separator in order to prevent subsequent excessive heating, and to also remove the refuse therefrom, prior to final disintegration and packaging or bagging thereof.

45 The present invention therefore contemplates provision of a simple, compact and efficient system for simultaneously cooling the forage and for automatically removing objectionable refuse from the wholesome product, thereby placing the latter in better condition for further treatment and final merchandizing.

Another specific object of my present invention is to provide simple and readily manipulable 50 instrumentalities for controlling the distribution

of material delivered from a forage drying system or the like, and for separating such materials into selective grades if desired.

A further specific object of this invention is to provide an improved cooling system wherein the temperature of the material is quickly and effectively reduced by substituting an abundance of fresh air for the hot drying gases previously used as a conveying medium for the particles during the drying operation.

Still another specific object of my present invention is the provision of an improved conduit assemblage for conducting a forage laden stream of air from one place to another so as to automatically remove heavy and undesirably large 15 particles of refuse or the like from finer grades of the material.

An additional specific object of the invention is to provide an improved cooling and separating system for granular and fibrous material, 20 which may be installed and operated at moderate cost, and which is dependable in actual operation.

These and other objects and advantages will be apparent from the following detailed description.

A clear conception of the several features constituting the present improvement, and of the mode of operating the improved cooling and separating system, may be had by referring to 30 the drawing accompanying and forming a part of this specification wherein like reference characters designate the same or similar parts in the various views.

Fig. 1 is a somewhat diagrammatic side elevation of a forage drying system having the improved cooler and separator embodied therein;

Fig. 2 is an enlarged central vertical section through a fragment of the improved cooling and separating system, showing the same in action; 40 and

Fig. 3 is a similarly enlarged transverse vertical section through the cooler and separator of Fig. 2, the section being taken along the line 3—3.

45 While the invention has been illustrated as being applied to a specific type of drying system especially adapted for the treatment of forage such as alfalfa, it is not the intent to thereby unnecessarily restrict the scope.

50 Referring to the drawing, the forage drying system shown in Fig. 1 by way of illustration, comprises in general a relatively large and elongated drier drum 5 rotatably supported upon a main foundation 6 by means of rollers 7; a 55

main suction or exhaust fan 8 having an axial inlet pipe 9 communicating directly with the delivery end of the drum 5 and also having a tangential peripheral discharge pipe 10 leading 5 into the upper end of a centrifugal separator 11; an auxiliary suction fan 12 having an axial inclined inlet duct or pipe 13 extending downwardly at an angle and beneath the lower material delivery end 14 of the main separator 11; an open hopper 15 disposed beneath the separator end 14 and having a lower end 16 in open communication with the open lower end 17 of the pipe 13; a shut-off gate 18 interposed within the pipe 13 between the hopper 15 and the fan 12; a second centrifugal separator 19 having an upper inlet pipe 20 which also constitutes the peripheral discharge conduit of the fan 12; and a two-way final material delivery conduit 21 associated with the lower discharge end of the 20 second separator 19.

The drier drum 5 has a series of internal material showering flights and is provided with a circuitous passage through which the forage is normally transported by hot gases and is simultaneously subjected to drying action, in a well known manner, and the mixture of hot gas and material is constantly withdrawn from the interior of the revolving drum 5 through the pipe 9 and is delivered to the initial separator 11 through the pipe 10. The main separator 11 is of the well known cyclone type, and is adapted to continuously separate the solid material from the gases, the granular material 22 being delivered by gravity toward the lower discharge end 14 and the 30 gases being discharged through a central upper outlet 23. The drier drum 5, fan 8 and separator 11 are all of well known construction and operation, and therefore require no further detailed disclosure and description.

The cooling and separating assembly constituting the present improvement and comprising the inclined pipe 13, the hopper 15 and the gate 18, is shown in detail in Figs. 2 and 3, and may be supported from the floor 24 by frame members 25. The hopper 15 may be swingably suspended from the lower end portion of the pipe 13 by means of a hinge 26, and the upper enlarged open end of the hopper 15 is preferably spaced some distance from the delivery end 14 of the main separator 11 so that the dried forage 22 may drop freely into the hopper by gravity, as illustrated in Figs. 1 and 2. As shown, the hopper 15 is square in transverse cross-section, but it may be round, and the lower constricted end 16 of the hopper should be in open communication with the pipe 13 at all times. The open lowermost end of the pipe 13 should also be unobstructed for free admission of abundant quantities of cooling air and for the discharge of abnormally heavy 50 particles 27 such as stones, pieces of metal or unusually large stems; and a coarse screen 28 may be inserted across the interior of the pipe 13 just beyond the hopper end 16. The shut-off gate 18 is slidably adjustable between guides 29 and is 55 adapted to be frictionally retained by these guides in any desired position of adjustment, so that the pipe 13 may be more or less restricted in cross-section by the gate 18, or it may be closed off entirely.

The secondary fan 12 and separator 19 are likewise of well known construction, and the pipe 13 preferably approaches the fan inlet at an inclination but without abrupt changes in direction. The pipe 20 which extends tangentially away 75 from the fan 12 leads tangentially into the upper

end of the second separator 19, and this separator is adapted to remove the granular cooled material from the cooling air and to deliver the latter to the atmosphere through an upper central outlet 30. The separated granular material 5 is deposited by gravity toward the two-way chute 21 which is ordinarily provided with a swingable gate for effecting interchangeable delivery of the material to either outlet or spout of the chute. From the chute 21, the finally cooled granular 10 material 22 may be delivered either into bags, or to a final disintegrator such as an impact pulverizer for further uniform reduction, and this final disposition or treatment of the product is also old and well known.

While the normal operation of the improved system should be generally apparent from the foregoing description, I will again present a short résumé thereof. When the drier system is in operation, the drum 5 and the rotors of the fans 20 8, 12, are being constantly revolved, and the material admitted to the inlet end of the drier drum 5 is being transported through the revolving drum by hot air or gases and is being simultaneously agitated by the internal flights of the 25 drum. The main fan 8 constantly withdraws the mixture of hot gases and material through the pipe 9 and delivers the mixture of material into the upper end of the main separator 11 through the pipe 10. In the separator 11 the dry granular 30 material is removed from the hot gases, the latter being discharged through the upper outlet 23 and the former being delivered by gravity through the open delivery end 14 of the cyclone separator and into the hopper 15. As the granular material 22 falls through the hopper 15, it entrains air from the ambient atmosphere and is initially cooled thereby. The auxiliary suction fan 12 is creating a relatively rapid flow of air into the open lower end 17 of the conduit 13, and this 35 entering cooling air upon striking the finer and lighter particles of material 22 passing through the outlet end 16 of the hopper 15, carries these lighter particles upwardly through the pipe 13. The heavier particles 27, however, gravitate 40 through the stream of cooling air which enters the pipe end 17, and drop upon the floor 24 directly beyond the open inlet end of the pipe 13 as clearly shown in Fig. 2. When a screen 28 is used, this screen will catch larger particles 45 of relatively light material and will retain the same, and the hopper 15 may occasionally be swung about its hinge 26 so as to permit removal of lodged material from the screen 28. Depending upon the setting of the shut-off gate 18, the 50 velocity of the stream passing through the pipe 13 may be varied, to thereby vary quantity of heavier particles 27 which are discharged from the lower end 17 of the pipe 13. When the gate 18 is fully open, there will be least obstruction 55 to the flow of air and solids to the fan 12, thereby separating only the heavier particles 27 from the mixture. If, however, the gate 18 is closed to a considerable extent, a greater number of particles 27 will be separated from the finer particles, 60 and the material may thus be graded. The mixture of fine material and cooling air which is sucked through the pipe 13 by the fan 12, is delivered to the upper end of the secondary separator 19 through the pipe 20. In the separator 19, 70 the cooling air is removed and delivered through the outlet 30, while the cooled granular material 22 is deposited by gravity through the chute 21 either into bags or to the final disintegrator.

From the foregoing description it will be ap- 75

parent that the present invention provides a simple and highly efficient cooling and separating system for quickly reducing the temperature of the product and for removing therefrom undesirably heavier grades of material. The system functions automatically and its operation is at all times visible, and no attention is ordinarily required. All portions of the improved cooler and separator are conveniently accessible for inspection and adjustment, and the degree of separation may be conveniently varied at any time. The relatively fine particles of the material 22 are subjected to cooling action both by the air entrained through the hopper 15 and by the abundant quantities of atmospheric air admitted through the open end 17 of the pipe 13, and the velocity within the pipe 13 may obviously be varied to suit different conditions of operation. While the screen 28 may be desirable, this screen may obviously be omitted without impairing the usefulness of the system, and the improved cooler and separator has been found highly effective in actual commercial use.

It should be understood that it is not desired to limit the present invention to the exact details of construction and to the precise mode of operation herein shown and described, for various modifications within the scope of the claims may occur to persons skilled in the art.

I claim:

1. In a system for treating a mixture of hot gas and granular material, a separator for removing the gas from the dry granular material and for delivering the latter into the ambient atmosphere, an upwardly inclined pipe having a laterally open lower end, a suction fan for producing a flow of air into said open end and upwardly through said pipe, a shut-off gate in said pipe upwardly beyond said open end, a hopper for delivering said granular material from the atmosphere downwardly into said pipe in advance of said gate and laterally beyond said open pipe end, and a screen spanning said pipe between said hopper and said gate. 15

2. In a cooling and separating system for hot granular material, an inclined pipe having an open lower end and a laterally upper inlet opening above the pipe bottom and directly adjacent said open end, means for creating a flow of air into said open end and through said pipe beneath said opening, a hopper for delivering granular material from the atmosphere into said opening, a gate for varying the cross-sectional area of said pipe beyond said inlet opening, and a screen 20 spanning said pipe between said inlet opening and said gate, said hopper being swingably mounted to permit free access to the delivery end of said inlet opening and to said screen. 25

CHARLES WESLEY BOAG.
